ARTHUR GEBBERT, OF ERLANGEN, GERMANY.

HIGH-FREQUENCY OSCILLATION SYSTEM FOR MEDICAL APPARATUS.

Application filed November 9, 1926, Serial No. 147,365, and in Germany December 16, 1925.

This invention relates to improvements in electrical systems for the production of high frequency oscillations, and has particular reference to a system of this type to be used 5 for medical purposes.

Systems that serve for the production of high frequency electrical oscillations for medical purposes may be protected from injurious heating in case of slight consumption 10 of energy or an absence thereof by connecting in parallel with the source of high frequency or the consumption circuit, or a part thereof, a loading resistance and a variable self-induction, the latter, however, only when 15 any self-induction that may be connected in series with the patient has been switched off. By means of suitable dimensioning of the self-induction coil or coils, there may be made to flow in the circuit including the patient 20 only a weak current which, however, cannot be caused to disappear and which, at the removal of the electrodes from the patient during an operation, still continues to produce weak sparks.

25 In accordance with the invention, the above difficulty is overcome by connecting a variable self-induction in parallel with a series connection consisting of a loading resistance and the patient with the movable part of the 30 regulating device connected between the patient and the loading resistance.

The inventive idea involved is capable of receiving a variety of expressions, some of which, for the purpose of illustrating the invention, are shown in the accompanying drawing; but it is to be expressly understood that said drawing is to be used merely for the purpose of facilitating the description of the invention as a whole and not to define the 35 limits thereof, reference being had to the appended claims for this purpose.

In the drawing—

Figure 1 is a diagrammatic illustration of a system embodying one form of the invention; and

Figure 2 is a similar view illustrating another form.

In the form of the invention shown in Figure 1 there is provided, in parallel with the 50 secondary winding of a transformer supplying high frequency current *a*, the self-induction coil *b*. To the two ends of the coil *b* there are connected in series the electrodes *c* and the loading resistance *d*, the electrodes 55 being adapted to be applied to a patient.

The movable contact element *e* which is displaceable along the coil *b* has its pivot or fixed point connected in circuit between the electrodes *c* and the loading resistance *d*. This arrangement is such that a displacement of the element *e* toward the right results in greater amperage in the electrode circuit and a movement thereof toward the left causes a short-circuiting of said electrodes. In the latter position of the element *e* the electrodes may be taken from the patient while the apparatus is in full operation without encountering the previously mentioned drawback. As many pieces of apparatus as desired, including the elements *b*, *c*, *d* and *e* may 60 be connected to the source *a* in parallel.

As illustrated in Figure 2 the system may also be arranged for use with two or more patients by the employment of a common loading lamp or resistance. In this case the high frequency current flows from the secondary of the transformer *f* successively through the electrode *g*, the common resistance *h* and other electrode *i*. In parallel with the resistance *h* and with each one of the electrodes *g* and *i* there are located the variable self-induction coils *k* and *m*, respectively, each having regulating devices in the form of movable contacts *n* and *o*. By displacing the elements *n* and *o* it is always 70 possible to bring about that one of the electrodes or the loading resistance is connected to the full potential or is short-circuited. Since in the latter case there is always present a path for the high frequency current which 75 is free from induction it is possible, in this case also, to remove the electrodes from the patient while the apparatus is in full operation without the occurrence of the sparking 80 previously mentioned.

The system renders possible, as is apparent, a corresponding extension for more than two patients if distributor resistances are connected to the terminals *g*, *i*, or several pieces of the apparatus, including the elements *g*, *h*, *i*, *k*, *m*, *n*, *o* are connected in parallel.

What is claimed is:

1. In an electrical system for the control of high frequency oscillations especially used in medical apparatus, the combination of a 105 high frequency transformer, a variable self-induction connected thereto and including a regulating element, and a loading resistance and electrodes in circuit with said induction, said regulating element being connected to 110

the circuit between said resistance and electrodes.

2. In an electrical system for the control of high frequency oscillations especially used in medical apparatus, the combination of a high frequency transformer, a variable self-induction in parallel therewith and including a regulating element, and a loading resistance and electrodes connected in series with said induction, said regulating element being connected to the circuit between said resistance and electrodes.

3. In an electrical system for the control of high frequency oscillations especially used in medical apparatus, the combination of a high frequency transformer, a plurality of variable self-induction coils connected in parallel with said source and each having a regulating device, a plurality of electrodes in circuit with said coils, and a common loading resistance in series with said regulating devices.

ARTHUR GEBBERT.
